US00D536326S

(12) **United States Design Patent** (10) **Patent No.:** **US D536,326 S**
Kim et al. (45) **Date of Patent:** **** Feb. 6, 2007**

(54) **MOBILE PHONE**

(75) Inventors: **Young-Sae Kim**, Los Altos, CA (US);
Chi-Young Ahn, Seoul (KR);
Young-Ju Yeo, Seoul (KR);
Chang-Hwan Hwang, Goyang-si (KR)

(73) Assignee: **Samsung Electronics Co., Ltd.**,
Suwon-Si (KR)

(**) Term: **14 Years**

(21) Appl. No.: **29/243,696**

(22) Filed: **Nov. 30, 2005**

(30) **Foreign Application Priority Data**

Jun. 15, 2005 (KR) 30-2005-0020018

(51) **LOC (8) Cl.** **14-03**

(52) **U.S. Cl.** **D14/138**

(58) **Field of Classification Search** D14/137,
D14/138, 147-148, 247-248, 144, 496, 156,
D14/341-347, 191, 192; 379/433.01-433.13;
455/575.4, 566, 575.1, 556.1, 556.2, 90.3,
455/41.2; D21/329, 331, 333; D16/208

See application file for complete search history.
